UNITED STATES PATENT OFFICE.

SILAS W. LOLLER, OF CAMERON, WEST VIRGINIA.

IMPROVEMENT IN REFRIGERATORS.

Specification forming part of Letters Patent No. **222,924**, dated December 23, 1879; application filed October 31, 1879.

To all whom it may concern:

Be it known that I, SILAS W. LOLLER, of Cameron, in the county of Marshall and State of West Virginia, have invented certain new and useful Improvements in Boxes for the Transportation of Butter; and I do hereby declare the following to be a full, clear, and exact description of the invention, such as will enable others skilled in the art to which it pertains to make and use it, reference being had to the accompanying drawings, which form part of this specification.

My invention relates to an improvement in boxes for the transportation of butter; and it consists in the peculiar construction of a sheet-metal frame which is to be inserted in an inclosing case or box, and which metal frame is to be filled with ice or cold water, and so shaped as to surround the trays or wooden frame holding the butter, and thus prevent heat from affecting the butter during transportation or storage, as will be more fully described hereinafter.

Figures 1 and 2 are vertical sections of my invention, taken at right angles to each other, showing the summer-trays. Fig. 3 is a plan view of the zinc frame in which the ice is placed for summer use. Fig. 4 is a vertical section of the box, showing the shelves used during cold weather.

a represents a suitable box or frame, in which the butter is to be transported and then set up in the merchant's store, to keep the butter until sold.

During all the months of the year except the very hottest ones the trays *c* are used in the frame, which frame is provided with the grooves *d* to receive them. Each tray is divided into a number of sections, which are just large enough to hold a print or roll of butter, and each tray can be drawn out so as to display the butter to the purchaser. With these trays *c* is used a door that is large enough to cover the whole side of the frame, so as to keep the heat from affecting the butter.

During the three or four hottest months of summer ice or water is absolutely necessary to keep the butter hard, both while sitting in the store ready for sale and during transportation. When ice is to be used the trays *c* are taken out, the door entirely removed, and then the

zinc frame *e*, in which the ice is placed, is inserted. Fitting in this frame *e* is a wooden frame, *g*, which has grooves cut in its inner sides to receive the trays *i*, and which wooden frame has secured to its outer end a portion of the end of the frame *a* and the door *h*.

The zinc frame is divided, by means of the openings in it for the flanges *l* of the frame *g* to fit in, into the chamber *n*, which extends down the back of the box, the two chambers *o*, which extend over and under the shelves, and the two chambers *r*, which extend along the sides of the shelves or trays. The ice is introduced into this zinc frame through the narrow door *s*, made along the top edge of the frame *a*, and from the chamber *n*, into which the ice is dropped, it can be pushed into all of the others by means of a stick.

The flanges *l* or projecting ends of the frame *g* rest against the inner sides of the top and bottom parts of the frame *a*, as shown in Fig. 2, and into these flanges may be passed screws for the purpose of holding the frame in place. The frame is also held in place by means of the parts *v*, which are secured thereto and form a part of the end of the frame *a*.

The tops of the trays *i* are covered with zinc, so as to be always kept easily cleaned.

It will be understood that in some cases air-inlet and air-outlet openings may be made to communicate with the cooling-chamber and preserving-chamber and external air, whereby a free circulation of cool air may be caused to pass through the preserving-chamber.

Heretofore refrigerators have been made in which a chamber provided with shelves is shown surrounded with a chamber to receive water or ice, and this is here disclaimed.

Having thus described my invention, I claim—

The metallic frame *e*, divided into the chambers *n o r*, in combination with the frame *g*, having the trays *i*, and the inclosing-frame *a*, having the door *s*, substantially as set forth.

In testimony that I claim the foregoing I have hereunto set my hand this 17th day of October, 1879.

SILAS W. LOLLER.
